UNITED STATES PATENT OFFICE.

JOHN A. FENTON, OF OAKLAND, CALIFORNIA.

DESIGN FOR A CHAIR.

48,969.

Specification for Design.

Patented May 2, 1916.

Application filed February 28, 1916. Serial No. 81,074. Term of patent 7 years.

To all whom it may concern:

Be it known that I, JOHN A. FENTON, a citizen of the United States, residing at Oakland, in the county of Alameda and State of California, have invented a new, original, and ornamental Design for Chairs, of which the following is a specification, reference being had to the accompanying drawing, forming part thereof.

The figure is a perspective view of a chair, showing my new design.

I claim:—

The ornamental design for a chair, as shown.

In testimony whereof I affix my signature.

JOHN A. FENTON.
